UNITED STATES PATENT OFFICE.

JOSEPHUS HARTMAN, OF PHILADELPHIA, PENNSYLVANIA.

DESIGN FOR A BISCUIT-CRACKER.

SPECIFICATION forming part of Design No. 17,757, dated October 4, 1887.

Application filed August 5, 1887. Serial No. 246,223. Term of patent 14 years.

To all whom it may concern:

Be it known that I, JOSEPHUS HARTMAN, a citizen of the United States, residing at Philadelphia, in the county of Philadelphia and State of Pennsylvania, have invented and produced a new and original Design for Biscuit-Crackers, of which the following is a specification, reference being had to the accompanying drawings, forming part thereof.

In the drawings, Figure 1 represents a perspective view in which the raised central portion is designed to simulate an oyster, while the surrounding portion simulates the half-shell, upon the concave face of which the oyster

rests. Fig. 2 is a longitudinal section of same, 15 taken through line x x of Fig. 1.

The outer face of the shell is convex.

I claim as my invention—

The design for biscuit-crackers herein shown and described, the same consisting of the raised 20 central portion simulating an oyster resting upon the concave face of the concavo-convex base portion, representing the half-shell thereof, as set forth.

JOSEPHUS HARTMAN.
